UNITED STATES PATENT OFFICE.

GEORGE CLARK, OF BROOKLYN, NEW YORK.

BUTTON-HOOK.

SPECIFICATION forming part of Letters Patent No. 277,232, dated May 8, 1883.

Application filed February 28, 1883. (No model.)

To all whom it may concern:

Be it known that I, GEORGE CLARK, of Brooklyn, in the county of Kings and State of New York, have invented a new and Improved 5 Button-Hook, of which the following is a full, clear, and exact description.

The object of my invention is to provide a new and improved button-hook which can be adjusted to occupy but very little space when 10 not in use.

Reference is to be had to the accompanying drawings, forming part of this specification, in which similar letters of reference indicate corresponding parts in all the figures.

Figure 1 is a longitudinal side elevation of 15 my improved button-hook, showing the hook contained in the casing. Fig. 2 is a longitudinal side elevation of the same, showing the hook withdrawn, parts being broken out and 20 others shown in section. Fig. 3 is a longitudinal edge elevation, showing the hook contained in the casing. Fig. 4 is a sectional plan view of the same on the line xx , Fig. 2.

The button-hook A, which is of the usual 25 construction, is provided in the lower end of its shank with a notch, B, and below the notch with a cross-pin, C, parallel with the prong of the hook and extending from opposite sides of the shank. The shank is inserted in a flattened 30 casing, D, provided in each side with a longitudinal raised part, E, for receiving the shank of the hook. The cross-pin C passes into the flattened part of the casing to guide the shank of the hook and to prevent it from 35 turning. The casing is provided in one edge and at the upper end with a slot, F, in which a latch, G, is pivoted, which has its inner edge beveled from near the upper inner corner toward the outer lower corner, as shown. That 40 end of the cross-pin C toward the beveled edge of the latch is beveled to fit against the said beveled edge. At that edge of the casing opposite the one provided with the slot F a cross-pin, H, is provided, against which the cross-pin C strikes to prevent withdrawing the shank 45 entirely from the casing. In place of providing the cross-pin H, part of the metal of the casing can be pressed inward to form a shoulder against which the cross-pin C can strike. 50 If the shank B is withdrawn from the casing, the beveled end of the cross-pin C strikes

against the beveled edge of the latch and throws the lower part of the latch outward and the upper part inward and into the notch B, whereby the latch will hold the shank of the hook in place and prevent pushing the same back into the casing, and the button-hook can then be used. If the shank of the hook is to be pressed back into the casing, the lower part of the latch G is pressed inward, whereby the 55 upper part will be removed from the notch and will release the shank. The casing is flat and occupies very little space, and does not require much material.

The hook-shank is sustained in the casing 60 when not in use, and does not occupy space, and is not apt to catch on the clothes or injure the person carrying it in the pocket.

No springs are required, and the device is 65 composed of few parts.

The casing being flat or oval, it has a very 70 convenient shape for holding it firmly in the hand while using the button-hook.

Having thus described my invention, what I claim as new, and desire to secure by Letters 75 Patent, is—

1. The combination, with the button-hook A, having a notch, B, of the casing D, and the latch G, pivoted thereto, substantially as herein shown and described, and for the purpose set 80 forth.

2. A button - hook having the cross-pin C at or near its rear end, in combination with the casing D E, provided with a flattened part, forming a groove, in which said pin slides, as 85 described.

3. In a button-hook case or holder, the combination of the pivoted latch G and sliding cross-pin C, correspondingly beveled, whereby as the button-hook is withdrawn the cross-pin causes the pivoted latch to lock in the 90 notch of the button-hook, as described.

4. The combination, with the button-hook A, of the casing D, the cross-pin C, the latch G, and the cross-pin H, substantially as herein 95 shown and described, and for the purpose set forth.

GEORGE CLARK.
